UNITED STATES PATENT OFFICE

105,421

DESIGN FOR A COMBINED ENDPIECE AND TEMPLE FOR AN OPHTHALMIC MOUNT- ING

Edward M. Splaine, Southbridge, Mass., assignor
to American Optical Company, Southbridge,
Mass., a voluntary association of Massachu-
sets

Application November 16, 1936, Serial No. 65,925

Term of patent 14 years

To all whom it may concern:

Be it known that I, Edward M. Splaine, a citizen
of the United States of America, residing at
Southbridge, in the county of Worcester and
State of Massachusetts, have invented a new,
original, and ornamental Design for a Combined
Endpiece and Temple for Ophthalmic Mountings,
of which the following is a specification, reference
being made to the accompanying drawing,
forming a part thereof.

Fig. 1 is a combined end piece and temple for
an ophthalmic mounting showing my new de-
sign;

Fig. 2 is a fragmentary perspective view on a
somewhat enlarged scale; and

Fig. 3 is a sectional view on line 3—3 of Fig. 1
looking in the direction of the arrows.

The dominant features of my design are shown
in full lines in the drawing.

I claim:

The ornamental design for a combined end
piece and temple for an ophthalmic mounting
substantially as shown and described.

EDWARD M. SPLAINE,
